United States Patent Office.

SIMON MINGES, OF ROCHESTER, NEW YORK.

Letters Patent No. 79,492, dated June 30, 1868.

IMPROVEMENT IN WEAR-PLATES FOR BOOTS AND SHOES.

The Schedule referred to in these Letters Patent and making part of the same.

TO ALL WHOM IT MAY CONCERN:

Be it known that I, SIMON MINGES, of Rochester, in the county of Monroe, and State of New York, have invented a certain new and useful Improvement in Wear-Plates for Boots and Shoes; and I do hereby declare that the following is a full and exact description thereof, reference being had to the accompanying drawings, making part of this specification.

Figure 1 is a perspective view of a shoe provided with my improvement.

Figure 2, a perspective view of the wear-plate detached.

Figure 3, a vertical section of the toe of a shoe with the wear-plate attached.

Like letters of reference indicate corresponding parts in all the figures.

My invention consists in a wear-plate for boots and shoes, combining a downwardly-projecting rim for covering and enclosing the sole, and an upwardly-projecting shield for protecting the upper leather at the toe; also, the combination, with a wear-plate enclosing the foot, of curved cross-pieces, and a dove-tailed bearing, which will allow expansion of the plate and retain it securely, as hereinafter set forth.

As represented in the drawings, A is the bottom of a boot or shoe, and B the wear-plate, attached thereto, extending around the toe and sole, preferably as far as the hollow of the foot. The wear-plate consists of a vertical rim, *a a a*, a dove-tailed bearing or bearing, *b*, and cross-connections *b' b'*, extending from side to side of the rim at suitable distances apart, as shown.

The rim *a a a* projects downward vertically sufficiently to cover the edge of the leather, which is fitted within clear to the bottom, making the whole flush, as shown in figs. 1 and 3, so as to receive the wear and protect the leather. It also projects upward at the toe, so as to form a shield, *x*, fig. 3, which serves to protect the upper leather.

The bearing or bearings *b*, and the connections *b' b'*, are fitted between the soles, as in fig. 3, and secured there to hold the wear-plate in place. The bearings are made of the dove-tailed form laterally, and the wedging form vertically, as shown. The connections are made curved backward, as indicated, and also, if desired, made slightly concave downward, to fit the transverse rounding form of the bottom of the foot.

This wear-plate insures several important advantages. The projection of the rim downward, so as to cover the edge of the bottom sole at the toe and sides, protects the leather, and, in a great degree, prevents wear at the points subjected to the greatest action. The sole is thus, as it were, encased at the edges. The shield *x*, in like manner, prevents wear to the upper leather at the toe. These two parts, *a* and *x*, therefore, serve as a perfect protection to the whole toe. The bearing or bearings *b* at the toe, inserted between the soles, cannot be withdrawn, especially when sewed, nailed, or pegged fast on each side of the dove-tail. The cross-connections *b' b'*, being embedded in the leather, effectually hold the body of the plate firmly; and not only this, but their curved form enables them to expand or contract the sides of the rim at pleasure to fit the outline of the sole by simply bending or straightening them, which is a matter of much importance in plates fitting around the sides of the sole. I am not aware that this effect has ever before been produced. The extension of the rim round to the bottom of the foot protects that whole portion where the greatest wear comes, and preserves the sole to the best advantage.

What I claim as my invention, and desire to secure by Letters Patent, is—

1. The combination, in the wear-plate B, of the rim *a*, covering or enclosing the sole, and the shield *x* protecting the upper, as herein set forth.
2. The combination, with the wear-plate B, of the curved cross-connections *b' b'*, for expanding the rim, and the dove-tailed bearing or bearings *b*, for shielding the toe, as herein set forth.

In witness whereof, I have hereunto signed my name in the presence of two subscribing witnesses.

SIMON MINGES.
